Primary Examiner—Louis S Zarfas*Assistant Examiner*—Eric L Goodman(74) *Attorney, Agent, or Firm*—Buchanan, Ingersoll & Rooney PC; Brian L. Belles(57) **CLAIM**

I claim the ornamental design for a high temperature disconnect union, as shown and described.

DESCRIPTION

FIG. 1 is a front perspective view of a high temperature disconnect union showing my new design;

FIG. 2 is a rear perspective view of the high temperature disconnect union of FIG. 1;

FIG. 3 is a left-side view of the high temperature disconnect union of FIG. 1;

FIG. 4 is a front view of the high temperature disconnect union of FIG. 1;

FIG. 5 is a rear view of the high temperature disconnect union of FIG. 1; and,

FIG. 6 is a right-side view of the high temperature disconnect union of FIG. 1.
